UNITED STATES PATENT OFFICE

ANTHONY J. MENTINK, OF TROY, OHIO

SIGN

Application filed September 29, 1928. Serial No. 309,157.

This invention relates to changeable signs or bulletin boards of the stationary type, and has for its main object the provision of a sign board of this character having a series 5 of detachable letter trays which are individually removable from the board, the letter trays having removable letters or indicia.

Another object of the invention is the 10 provision of a sign board of the character mentioned having letter trays detachably supported on the board in a novel manner so that they may be very quickly and easily mounted in position or individually removed from the board.

Other objects and advantages of the invention will be apparent from the following description and from the accompanying drawing, in which—

20 Fig. 1 is a front elevation of a bulletin board embodying the present invention, part of the board frame being broken away;

Fig. 2 is a vertical section through the top of the board on the line 2—2 of Fig. 1;

25 Fig. 3 is a section on the line 3—3 of Fig. 1;

Fig. 4 is a section on the line 4—4 of Fig. 1, and

Fig. 5 is a front view of one end of a tray.

30 The sign of the present invention is of the stationary type adapted for the support of a number of legends and indicia in such manner as to permit them to be readily changed. Bulletin boards or signs of the present invention are particularly desirable in that they

35 permit the words or phrases to be applied to removable trays wherever this is most convenient, and then the trays may be very quickly applied to or positioned on the board.

40 The application of the letters to the trays need not take place while one is standing in front of the board, which may be in a public place or in view of many observers, but this operation can be done at a desk where one

45 would not be interfered with nor confused. The application of the trays to the board, which is a comparatively simple operation and one in which confusion would not be 50 likely, is then a very simple matter even if

the sign is in a public place and observed by many.

Referring to the drawing, the sign or bulletin board of the present invention embodies a main back board or sign support designated generally 10 and a series of trays 11 which support a series of letter pieces 12. The back board or support is shown in the form of a rectangular sheet of metal 14 of any suitable thickness and size. This sheet is peripherally enclosed by a frame 15 which may be of wood or other suitable material, each side of this frame preferably having a slot 15 which receives the edge of the metal sheet 14 as shown in Fig. 2. This sheet is provided along each side with a series of tray supports or clips 16. As shown in Fig. 4 these clips may be integrally struck out of the single sheet of metal forming the back plate so as to provide upwardly extending fingers 17 and longer downwardly extending fingers 18 which are spaced a little distance away from the main plane of the sheet 14 so that they may receive the ends of the letter trays 11. The vertical distance between a finger 18 of one clip and the adjacent finger 17 of an adjacent clip is such that the tray may be inserted by moving it upwardly behind the depending finger 18 as far as it will go, after which the lower side of the tray may be moved towards the plate 14 clearing the top of the finger 17, and then the tray may be moved downwardly so that it is supported on the bottom of the finger 17 and retained thereby. Thus the trays may be individually applied to or removed from the board, the trays being supported in such a way that only slight relative movement between a tray and the board, is necessary in mounting it in place or in its removal. In the mounting of the trays or during their removal, such operations being accomplished without using tools of any sort, the clips themselves are not disturbed as it is not intended that they should be bent or moved in any way.

Each letter tray 11 comprises a strip of suitable material, preferably sheet metal, having an upturned bottom portion which is reversibly bent at 20 to form a groove or

crook adapted to receive the bottom portions of letter pieces 12. The crook portion of the metal strip is slightly S or ogee shaped, so that the most narrow portion of the groove or crook is at 22, the distance across the space at this point being such as to cause the letter pieces to be pinched at a point somewhat above their lower edges so that they will lie flat against the back 23 of the tray. The out flaring end of the bent portion 20 permits the letter pieces to be easily applied. Means for holding the top portions of the letter pieces in position need not be provided as the letter pieces are held in their proper positions along the back 23 in the manner mentioned. These letter pieces are formed of any suitable thin durable material of sufficient rigidity so that they will lie flat on the trays, and being supported in the manner described they may be very easily and quickly removed from or applied to the trays in an individual manner so as to form the desired word, phrase or indication.

It will now be apparent that the letter pieces may be conveniently applied to the various trays at a suitable or convenient place which may be far from the board itself. The trays may then be carried to the board and quickly mounted in position in an individual manner and merely by slight movements of the trays in applying them to the clips. Furthermore a number of extra trays may be employed so that an announcement may be composed and prepared ahead of time and put aside until needed, when the prepared trays are quickly substituted for those on the board. To remove the trays from the clips it is merely necessary to move a tray vertically upward so that the top of the tray engages the upper portion of the finger 18 at each end of the tray. The lower portion of the tray is then pulled out slightly away from the sheet or plate 14 after which the tray may be removed by downward movement with relation to the board so as to free it entirely from the holding clips. To permit the handling of the trays, and their insertion and removal in a convenient manner, they are preferably provided with finger pieces 25 which are struck up from the trays near each end portion. These finger pieces 25 may be easily grasped between the thumb and finger of each hand when the trays are being mounted or removed from their positions on the board.

55 The overturned lower edge 20 of a tray preferably extends only to a point 26 spaced a little distance from the end of the tray so that the end of the tray is flat and may readily be received by the finger 17 which holds the bottom portions of the trays. The end of the upturned bottom portion of the tray forms a stop, which cooperates with the finger 17 to position the tray definitely against endwise movement on the board. Preferably the series of clips 16 is sufficiently close

to the inner edge of the frame 15 which surrounds the board so that the trays are limited by the frame itself against any endwise movement across the board. This permits the trays to be easily mounted in position and positions the trays against endwise movement during the time they are being applied to or removed from the clips.

While the form of apparatus herein described constitutes a preferred embodiment of the invention, it is to be understood that the invention is not limited to this precise form of apparatus, and that changes may be made therein without departing from the scope of the invention which is defined in the appended claims.

What is claimed is:

1. A sign of the class described comprising a main supporting plate, a series of trays each detachably supported so as to be individually removable from said plate without disturbing other trays, a series of letter pieces each detachably supported by a tray so as to be individually removable from the tray without disturbing other letter pieces, the tops of the letter pieces being adjacent the tops of the trays by which they are supported and a frame surrounding said main supporting plate and retaining said trays against endwise movement.

2. A sign of the class described comprising a main metal supporting plate provided with a series of integrally stamped out attachment clips, a series of metal trays removably held in said clips so that they may be quickly individually removed from or inserted in said clips, and a series of letter pieces detachably supported by said trays in an individual manner, the height of each tray being substantially equal to the height of the letter pieces.

3. A sign of the class described having a main supporting plate provided with a series of attachment clips, a series of trays detachably supported in an individual manner on said clips, said clips being arranged in pairs each pair comprising a comparatively long downwardly extending clip in which the top of an end of a tray is received, and a comparatively short clip adapted to receive the bottom of an end of a tray, the space between the bottom of the long clip and the bottom of the short clip being less than the height of the tray, and the trays being insertable into the clips by slight vertical and rearward movement of the tray with respect to the back plate, and a series of letter pieces detachably supported by said trays.

4. A sign of the class described comprising a main metal plate having a series of attachment clips struck up from said plate and adapted to engage the corner portions of letter trays, a series of trays detachably supported in an individual manner by said clips and adapted to be inserted into their supported positions by slight upward, rearward

and downward successive movements of said trays without alteration of said clips, a series of letter pieces detachably supported by said trays, and a frame surrounding said main back plate and retaining said trays against 5 endwise movement.

5. A sign of the class described comprising a back supporting plate, a series of trays detachably supported in an individual manner on said plate, and a series of letter pieces 10 individually supported by said trays in a detachable manner, each of said trays comprising a sheet of metal bent up at its lower edge so as to form a crook receiving the lower portion 15 of said letter pieces, and means struck out integrally from said trays adjacent each end of said trays forming finger pieces by which the trays may be handled.

In testimony whereof I hereto affix my signature.

20 ANTHONY J. MENTINK.
